UNITED STATES PATENT OFFICE.

FRANK W. COOLBAUGH AND KARL DINGERTZ, OF EASTON, PENNSYLVANIA.

RAILWAY-CAR.

SPECIFICATION forming part of Letters Patent No. 651,795, dated June 12, 1900.

Application filed June 14, 1899. Serial No. 720,507. (No model.)

To all whom it may concern:

Be it known that we, FRANK W. COOLBAUGH, a citizen of the United States, and KARL DINGERTZ, a citizen of Sweden, residing at Easton, 5 in the county of Northampton and State of Pennsylvania, have invented certain new and useful Improvements in Railway-Cars, of which the following is a specification.

This invention relates to improvements in 10 railway-cars, and especially to cars for transporting freight, coal, gravel, &c.

The object of our invention is to provide a new and improved railway-car which is simple in construction, strong and durable, not 15 expensive, composed of few parts, and reliably, safely, and securely constructed.

In the accompanying drawings, forming a 20 part of this specification, and in which like letters of reference indicate like parts in all the views, Figure 1 is a plan view of our improved car. Fig. 2 is a vertical transverse sectional view on the line 2 2, Figs. 1 and 4, on an enlarged scale. Fig. 3 is a plan view 25 of the filling floor-plate. Fig. 4 is a plan view of the floor-framing. Fig. 5 is a vertical longitudinal sectional view on the line 5 5 of Figs. 1 and 4. Fig. 6 is a vertical sectional view on the line 6 6 of Fig. 4. Fig. 7 is a vertical longitudinal sectional view on the line 30 7 7 of Fig. 1. Fig. 8 is a horizontal sectional view on the line 8 8 of Fig. 7. Fig. 9 is a plan view of the hopper. Fig. 10 is a plan view of a corner of the car. Fig. 11 is a side view 35 of a corner of the car. Fig. 12 is a face view of a hopper hinge-bar. Fig. 13 is a plan view of the central portion of a car of modified construction. Fig. 14 is a vertical transverse sectional view through the car on the line 40 14 14 of Fig. 13. Fig. 15 is a vertical detail transverse sectional view on the line 15 15 of Fig. 13.

The floor-frame of the car is constructed 45 with two side sills A and the two center sills C and D, all composed of rolled-steel I-beams and extending the entire length of the car. The center sills C and D are arranged at a comparatively-short distance from each other and an equal distance from the longitudinal central line of the floor-frame. These floor- 50 sills are connected at each end of the floor-frame by an end cross-piece E, which is made of malleable iron with a web a on the outer

side and the top and bottom flanges b and c, said flanges gradually increasing in width from the end toward the center, so that the 55 inner edge of this end cross-piece is at right angles to the sills and the outer line will incline outward from the ends to the nearest center sill, that part of the outer surface of the cross-piece between the center sills being 60 parallel with the inner edge. The cross-piece E is provided on its inner surface and between its top and bottom flanges b and c with vertical webs d in pairs, flared at the top and bottom toward the top and bottom flanges b 65 and c, so as to leave a space between the inner surfaces of the webs d of such size and so shaped as to adapt it to receive the end of sill A, B, or C, as shown in Fig. 6, and these webs are provided with a central boss e, 70 through which a bolt or rivet F can be passed, which is also passed through a hole suitably provided in the end parts of the web of the floor-frame sills. Additional webs or ribs f are provided between the top and bottom 75 flanges of the end cross-pieces to reinforce the same, as shown in dotted lines in Fig. 4.

The car is of a type of car known as a "hopper-car" and is provided in each half of its floor-frame with two transverse beams G 80 and H, separated from each other a distance equal to the top opening of the hopper, which transverse beams are composed of channel-bars fitting between the sills and secured to the same by angle-pieces g, which are riveted 85 to the webs of the sills and transverse channel-bars, as shown in dotted lines in Fig. 4. Diagonal braces I, composed of channel-bars or I-beams, are riveted at their ends to the inner surface of the side sills, near the outer 90 ends thereof, and to the center sills at or near the junction with the transverse channel-bars G. These braces I are provided for the purpose of preventing distorting of the floor-frame and at the same time support the 95 car-floor plates J, which cover the entire car-floor, with the exception of the hopper-openings and that part of the floor-frame between the center sills where they cross the hopper-openings. The floor-plates J rest upon the 100 sills, to which they are riveted, and abut against the top flanges of the end pieces E.

The floor-plate K for covering the space between the center sills over the hopper-open-

ing have their corners cut out, as at *k*, Fig. 3, to form the end tongues *k'*, which are bent slightly out of the plane of said plates, so that when the plate *K* rests upon the flanges of 5 the center sills the tongues can be passed under the edge parts of the floor-plates *J*. The floor-plate sections *K* are held in place on the tops of the center sills by means of malleable-iron angle-clips *L*, which bear against 10 the under sides of the top flanges of the center sills and are riveted to the under side of the plate-section *K*, as shown in Fig. 3, thereby avoiding the necessity of weakening the center sills by rivet-holes.

15 The ends *L'* of the hopper are formed of metal plates, which are secured on the upper surfaces of the top flanges of the side sills *A* and are inclined inward and downward, as shown in Fig. 2, and these hopper ends are 20 formed of one piece, with the inclined hopper-bottom *M* secured at its upper edge to the top flange of a transverse channel-bar *G*, which hopper-bottom is reinforced by angle-bars *N*, riveted to the under side thereof.

25 The hopper-gates *O*, which can be opened in any suitable way and by any suitable mechanism, consist of metal plates riveted to malleable-iron hinge-bars *P*; which are hinged to hinge-clips *P'*, secured to the transverse channel-bars *H*, said hinge-bars extending down to the bottom edge of the gates.

As shown in Fig. 9, the hopper-bottom *M* is recessed, as at *M'*, so as to fit on the center sills *C D*.

35 The side and end walls of the car are formed of rolled-steel channel-bars *Q*, the bottom flange of the lower bar extending outward and resting upon the floor-plates *J*, and is secured by means of rivets *q*, which are passed 40 through said bottom flange of the lower channel-bar, through the floor-plate, and through the outer top flange of the I-beam side sill *A*. The bottom flange of the top channel-bar *Q* rests upon the top flange of the lower channel-bar *Q*, and these flanges are secured to each other by rivets *q'*, so that the interior of 45 the car will be entirely smooth and the flanges of the channel-bars will extend outward. The webs of the channel-bars *Q* abut at the corners of the car, as shown in Figs. 10 and 11, and are connected with each other at each corner by a vertical malleable-iron angle-piece *R*, which is applied on the outer sides of the webs of the channel-bars *Q* and is riveted to 50 the same. The angle-piece is provided midway of its height with a horizontal hollow rib *R'*, adapted to receive the end parts of the abutting flanges of the upper and lower channel-bars *Q*, and this rib is rounded between 55 the ends of the said flanges on the sides and ends of the car, as shown at *R²* in Fig. 10. The rib *R'* is secured to the flanges of the channel-bars by rivets *r*, passed through said rib and through the end parts of the flanges 60 of the channel-bars. At the upper end the angle-piece *R* is provided with an outwardly-extending flange *S*, which rests against the

under side of the top flanges of the channel-bars *Q*, and is shaped in the form of a quadrant like the parts *R²* of the rib *R'*, so as to 70 fill the space between the ends of the top flanges of the side and end top channel-bars *Q*, said flange *S* being rabbeted, as at *S'*, so that the quadrant part of the flange between the ends of the top flanges of the channel-bars *Q* will be flush with the upper surfaces of the top flanges, thus giving the top of the corner of the car a finish. The bottom flange *T* of each angle-piece *R* is finished in the same manner, but reversed, so that the quadrant part of the bottom flange *T* of the angle-piece *R* rests directly upon the floor-plate *J*. These angle-pieces not only impart the proper finish to the corners of the car, but they stiffen the same and firmly unite the angle-bars of 85 the ends. If desired, two or more braces *W* may be riveted to the inner surfaces of the side walls of the car and to the floor between the central transverse channel-bars *H H*.

In order to relieve the center sills *C* and *D* 90 of some of the load on the car-floor and in order to transmit some of this load to the side sills, and thereby utilize the advantage of the strong truss formed in the sides of the car by riveting the channels together, we provide a 95 transverse truss at the center of the car, the ends of the truss having abutments on the side sills and the central part of the truss supporting the center sills at or near the middle of their lengths. To the inner surfaces of 100 each side sill *C* and *D* a malleable-iron shoe *V* is fitted, so as to rest upon the bottom flanges of said sills, and the shoe is secured to the side sills by rivets *v'*. Each shoe is provided in its exposed surface with a pocket 105 for receiving the end of a substantially V-shaped channel-bar *X*, the flanges of which project downward, the flat portion *X'* of said channel-bar extending over the tops of the center sills *C D*. The car-floor *J* must be cut 110 out between the points *V²* *V²* to permit said channel-bars *X* to pass over the center sills. A supporting and filling piece *Y*, made of 115 malleable iron, is shaped to fit between the inner faces of the center sills and is provided with top and bottom flanges which fit against the inner top and bottom flanges of the center sills, and this supporting and filling piece *Y* is provided with two bolt-sleeves *Y'*, which are integral with the filling-piece and are connected by a web *Y²*. Bolts *Z* are passed 120 through the web of the channel-bar *X*, forming a truss, and through said sleeves *Y'*, and nuts are screwed on the ends of the said bolts. The weight of the center channel-bars and 125 the load on them at the center of the car bears upon the filling and supporting piece *Y*, which in turn is supported by the bolts *Z*, which themselves are supported by the truss formed of the channel-bar *X*, having 130 its ends rested in the shoes *V* on the side sills. The bottom edges of the flanges of the channel-bar *X* are not in contact with the tops of the flanges of the center sills, but slightly

above the same, so that any slack can be taken up by tightening the nuts of the bolts Z.

We do not limit ourselves to a truss formed of channel-bars nor to the exact formation 5 and construction of the filling and supporting piece X, as both these elements can be changed more or less without departing from the spirit of our invention, nor do we confine ourselves to the use of a transverse truss of any kind 10 on hopper-cars only, as a transverse truss can be used to the same advantage on gondola cars, coke-cars, and, in fact, cars of all kinds.

Having described our invention, what we claim as new, and desire to secure by Letters 15 Patent, is—

1. In a railway-car floor, the combination with flanged sills, of cast end pieces provided on the inner sides with pockets for receiving the ends of the flanged sills and bolts passed 20 transversely through the sides of the pocket and those parts of the sills within the pockets, substantially as herein shown and described.

2. In a railway-car-floor frame, the combination with sills, of end pieces formed with a 25 web and top and bottom flanges, vertical webs or ribs between said top and bottom flanges, which webs or ribs have their ends flared so as to form a space between them for receiving 30 the ends of the sills and means for securing the sills in the pockets formed between said webs or ribs, substantially as herein shown and described.

3. In a hopper railway-car the combination with 35 rolled metal sills and transverse beams of a hopper in the floor-frame transversely to the length of the floor-frame, floor-plate sections resting on those parts of the central sills extending across the hopper and clips riveted 40 to the under side of said floor-plate sections and resting against the under sides of the top flanges of the central sills, substantially as herein shown and described.

4. In a railway-car, the combination with 45 a floor-frame, of side and end walls formed of flanged bars placed longitudinally, one upon the other and riveted to each other, through the abutting flanges, and malleable-iron corner-pieces resting on the outer surfaces of the 50 flanged bars riveted to said flanged bars and having hollow ribs for receiving the ends of the flanges of the side and end wall bars, substantially as herein shown and described.

5. In a railway-car, the combination with 55 a floor-frame, of side and end walls formed of flanged bars placed one upon the other, vertically, and their abutting flanges riveted to each other, the bottom flanges of the bottom flanged bars being riveted to the floor-frame, 60 and malleable-iron corner-pieces applied on the corners of the car on the outside and riveted to the flanged bars forming the sides and ends and to the flanges of said end and side bars, substantially as herein shown and described.

6. In a railway-car, the combination with

a metal floor-frame, of floor-plates on the metal frame, side and end walls formed of flanged bars, placed one upon the other, vertically, the abutting flanges of the flanged bars being 70 riveted to each other and the bottom flanges of the lower flanged bars, resting upon the floor-plates, being riveted to said floor-plates, floor-frame and side sills, and malleable-iron corner-pieces applied on the outside of the 75 flanged bars at the corners and riveted thereto, substantially as herein shown and described.

7. In a railway-car, the combination with a floor-frame of side and end walls, of a car-body, formed of flanged bars resting one upon the other, vertically, the abutting flanges of the flanged bars being riveted to each other and the bottom flanges of the bottom flanged bars being riveted to the floor-frame, of a 85 malleable-iron vertical corner-piece applied on the outer side of the flanged bars at each corner, which corner-pieces each have an external hollow rib for receiving the end parts of the abutting flanges of the side and end 90 flanged bars, substantially as herein shown and described.

8. In a railway-car, the combination with a floor-frame of side and end walls, of a car-body formed of flanged bars resting one upon the other, vertically, the abutting flanges of the flanged bars being riveted to each other and the bottom flanged bars riveted to the floor-frame, of a malleable-iron vertical corner-piece applied on the outer sides of the 100 flanged bars at each corner of the car, which corner-pieces each have an external hollow rib for receiving the end parts of the abutting flanges of the side and end flanged bars, that part of the hollow rib between the ends 105 of the flanges of the side and end flanged bars being rounded on a quadrant-line, substantially as herein shown and described.

9. In a railway-car, the combination with a floor-frame of side and end walls formed of 110 channel-bars placed one upon the other vertically, the abutting flanges of the channel-bars being riveted to each other, vertical malleable-iron corner-pieces applied on the outer side of the car and provided with top and bottom flanges which are riveted to the top 115 flanges of the top channel-bars forming the side and end of the car and the bottom flanges riveted to the bottom flanges of the bottom channel-bar of the sides and ends of the car, 120 substantially as herein shown and described.

10. In a railway-car the combination with a floor-frame of the side and end walls formed of channel-bars placed one upon the other vertically and malleable-iron vertical corner-pieces applied on the outside of the channel-bars and riveted thereto and provided with top and bottom flanges rabbeted to receive 125 the end parts of the top and bottom flanges of the channel-bars and rounded off at the 130 outer edges, substantially as herein shown and described.

11. In a railway-car, the combination with side and center sills for the floor-framing, of a transverse truss resting on the side sills and a supporting-piece between the center sills, which supporting-piece is suspended from said truss, substantially as herein shown and described.
12. In a railway-car, the combination with side and center sills for the floor-framing, of a shoe on the inner side of each side sill, a transverse truss having its end rested on said shoes, and means for supporting the center sill from said truss, substantially as herein shown and described.
13. In a railway-car, the combination with a side sill and center sills for the floor-framing, of a shoe on the inner side of each side sill, a bent rolled metal beam having its end rested on said shoes and extending over the center sills and a supporting and filling piece between the center sills and means for

supporting the said filling-piece from the bent transverse beam, substantially as herein shown and described.

14. In a railway-car, the combination with the side sills and center sills for the floor-framing of a transverse bent rolled-metal beam having its ends supported by the side sills and extending over the center sills, a supporting and filling piece between the center sills and having bolt-sleeves made integral therewith and bolts passed through said sleeves and through the transverse beam and nuts on said bolts, substantially as herein shown and described.

Signed at Easton, in the county of Northampton and State of Pennsylvania.
